UNITED STATES PATENT OFFICE.

LEWIS W. NELSON, OF PHILADELPHIA, PENNSYLVANIA.

DYNAMO-ELECTRIC MACHINE.

1,038,494.

Specification of Letters Patent. Patented Sept. 10, 1912.

Original application filed May 16, 1910, Serial No. 561,546. Divided and this application filed November 15, 1910. Serial No. 592,488.

To all whom it may concern:

Be it known that I, LEWIS W. NELSON, a citizen of the United States, residing in Philadelphia, Pennsylvania, have invented 5 certain Improvements in Dynamo-Electric Machines (being a division of my application for patent for dynamo-electric machines filed May 16, 1910, Serial No. 561,546,) of which the following is a specification.

One object of my invention is to provide a dynamo electric machine capable of use either as a generator or as a motor and particularly adapted for direct connection 15 to an internal combustion engine, in order that said engine may be cranked by the operation of the machine when the latter is supplied with current, and may also, when working on its own fuel, operate said 20 machine to generate an electric current with which to charge a battery used for starting or for any other purpose.

A further object of my invention is to provide a dynamo electric machine particularly adapted for use in connection with an 25 internal combustion engine and whose revolving element shall be particularly designed to replace the fly wheel of such an engine.

30 I also desire that the machine shall be of a relatively compact and substantial construction, with its parts so arranged as to occupy a minimum space and of such design as to require but little if any attention 35 under operating conditions.

I further desire to provide a dynamo electric machine of such a construction as will particularly adapt it for mounting between an internal combustion engine and the clutch 40 whereby power from said engine may be transmitted at will to any desired driven machine.

These objects and other advantageous ends I secure as hereinafter set forth, reference being had to the accompanying drawings, in which the figure is an enlarged vertical section of a machine constructed according to my invention, showing the preferred arrangement of its parts.

50 In the above drawings, 1 represents one end of an internal combustion engine of any desired type having a main shaft indicated at 2. To the crank case or other suitable part of the engine frame is attached 55 the inclosing casing 3 of my dynamo elec-

tric machine which in the present case is of the revolving armature type. The rear end 4 of said case has mounted on its inner face within said casing 3 a field yoke 5^a carrying a series of pole pieces 5 on which 60 are placed the field magnet windings 6. The armature of the machine, as indicated at 7, includes a cylindrical shell 8 concentric with the engine shaft 2, having an inwardly projecting flange 9 directly bolted 65 to a flange 2^a which in the present instance is formed integral with said shaft. At the end of the shell 8 opposite that connected to the shaft, is an outwardly extending annular web 10 carrying an annular toothed 70 frame 11^a on which is mounted a laminated ring 11. The armature windings are disposed around this casing and core in the manner well understood by those skilled in the art, and are positioned by the teeth of 75 said frame. This armature is revoluble immediately adjacent the faces of the pole pieces of the field magnets and it is noted that the web 10 carrying the armature core and windings is overhung as indicated at 80 12 in order to coöperate with a similarly overhung portion 13 of the shell 8 to support and hold in place the segments 14 of the commutator, which is mounted on the exterior surface of the said shell within the 85 cavity defined by the circle of field magnets. Between these latter are mounted the required number of brushes 15 which may be carried in any desired or suitable form of boxes 16, shown in the present instance as 90 supported on a body 17 of insulating material mounted upon the field magnet yoke or ring.

From that face of the disk or web 10 carrying the armature core and opposite the latter, there projects a slightly flared flange 18 serving as one member of a clutch, whose second member 19 has a portion 20 designed to coöperate with said part 18 and mounted on an extension 2^b of the engine shaft 2; said shaft in the present instance being provided with a head 2^c while the clutch member 19 has a tubular portion 21 extending concentrically with the extension 2^b within the shell 8 of the armature. Between the end of said part 21 and the head 2^c is a spring 22 normally tending to hold the two members of the clutch in their coupled positions.

The member 19 has bolted or otherwise 110

2
attached to it a grooved collar 23 splined to a shaft 24 connected to any desired mechanism which it is wished to drive. In order to make a tight connection the fixed casing 5 3 of the generator and the revolving armature 7, one of these two members is provided with a semi-circularly grooved lip 25 into which projects a rib 26 carried by the other member.

10 If it is desired to start the engine, current is supplied to the dynamo electric machine in any suitable manner whereupon said machine acts as a motor and turns the crank shaft of the engine until such time as the 15 latter starts and runs under its own power. Thereafter in addition to driving any load to which it may be connected, said engine may be used to operate the dynamo electric machine as a generator to provide current for the engine ignition system or for 20 any other purpose.

It is to be noted that the distribution of material in the armature is such that this latter is particularly adapted to act as a fly 25 wheel and as a matter of fact is designed to replace this particular element of the engine to which it is attached. By mounting one of the clutch members on this armature structure it is possible to assemble the various parts in a relatively small space immediately adjacent the engine itself, especially since the necessity of an independent fly wheel is obviated. It will be noted that the clutch operating spring is contained 30 within the body of the dynamo electric machine whose commutator is likewise so arranged that it economizes space to the 35

greatest possible extent. Moreover this machine is interposed between the shaft to be driven and the driving engine so that the apparatus as a whole is essentially compact; this characteristic being particularly due to the employment of a discoidal armature and to the mounting of the commutator within the cavity provided by the armature and 40 field magnets. 45

I claim:

The combination in a dynamo electric machine of a closed casing; a field yoke mounted on one end of said casing within 50 the same; a shaft extending through the casing; a series of pole pieces mounted on the yoke and projecting in lines parallel to the shaft; field windings mounted on said pole pieces; a cylindrical structure fixed to 55 the shaft in position to be inclosed by the pole pieces and their windings; said cylinder having a flange at one end; a commutator mounted on the cylinder; an armature disk fixed to said cylinder and having a portion coöperating with said flange thereof to retain the commutator in place; and an armature with its core carried by said disk and having an air gap lying in a radial plane of the shaft between itself and the 60 pole pieces. 65

In testimony whereof, I have signed my name to this specification, in the presence of two subscribing witnesses.

LEWIS W. NELSON.
